UNITED STATES PATENT OFFICE.

THOMAS J. STURTEVANT, OF WELLESLEY, MASSACHUSETTS, ASSIGNOR TO STURTEVANT MILL COMPANY, OF BOSTON, MASS., A CORPORATION OF MASSACHUSETTS.

SEPARATOR.

1,350,626.

Specification of Letters Patent. Patented Aug. 24, 1920.

Application filed July 24, 1917. Serial No. 182,407.

To all whom it may concern:

Be it known that I, THOMAS J. STURTEVANT, a citizen of the United States, residing at Wellesley, county of Norfolk, and State 5 of Massachusetts, have invented an Improvement in Separators, of which the following description, in connection with the accompanying drawings, is a specification, like characters on the drawings representing 10 like parts.

The invention hereinafter described relates to separators for grading materials, and is an improvement upon the separator shown in my application, Serial No. 173,784, 15 filed June 9, 1917.

This separator comprises an inclined casing containing screens which are percussively vibrated to facilitate the flow of the material to be graded along and through the 20 screens. It is desirable to have convenient access to the screens for the purpose of inspection, replacement and repair thereof.

One of the objects of the invention is to provide simple and effective means for percussively vibrating the screens, which may be lifted with the cover of the casing when the latter is opened.

Another object of the invention is to provide an improved mechanism for percussively vibrating a screen, which will permit blows of different force to be imparted thereto, and thereby increase the efficiency 30 of the screening action.

The means for percussively vibrating the screen shown in said patent, comprises swinging hammers pivotally connected to a rotor, and adapted to strike the end of a pin projecting down through the cover toward the screen. In the operation of this mechanism, on commencement of the rotation of the hammers or on slow rotation thereof, there is a tendency for their ends to abut against the upper end of the pin and have an end thrust against the same which may 40 react and tend to lift the cover from the casing.

Still another object of the invention is to provide a hammer mechanism having means for preventing the occurrence of this.

With the aforesaid and other objects in view, the character of the invention may be best understood by reference to the following description of one good form thereof, shown in the accompanying drawings, 50 wherein:

Figure 1 is a vertical section through the

separator shown herein as embodying the invention, the open position of the cover being indicated by broken lines;

Fig. 2 is a transverse section taken on line 2—2 of Fig. 1;

Fig. 3 on an enlarged scale is a vertical section showing the hammer mechanism and portions of the casing cover and screens;

Fig. 4 is a sectional detail of the pin for 65 transmitting the blows from the hammers to the lower screen;

Fig. 5 is a vertical section taken on line 5—5 of Fig. 4;

Fig. 6 is a transverse section taken on line 70 6—6 of Fig. 4;

Fig. 7 is a diagram showing the sequence of hammer blows for the lower screen; and

Fig. 8 is a diagram showing the sequence of blows for the upper screen.

75

Referring to the drawings, the separator shown therein as embodying the invention comprises an inclined casing 1 mounted on a support 3 and having a cover 5 connected at its upper end by hinges 7 with the casing. 80 The lower free end of the cover is adapted to rest upon a bar 11 extending transversely of the casing adjacent the lower end thereof.

One or more screens may be mounted in this casing; in the present instance of the 85 invention, a lower fine screen 13 is provided resting on springs 15 on supports 17 on the bottom of the casing. An upper coarse or scalper screen 21 is mounted in the casing above the lower screen, and is suspended 90 from the cover by hangers 23 (Fig. 2).

The mechanism for percussively vibrating the screens comprises rotors 25, in the present instance of the invention, in the form of split hubs fast on horizontal shafts 27 journaled in bearings in brackets 31 mounted on the cover. Each of these rotors has strikers or hammers 33 pivotally connected thereto adapted to be carried around by said rotor and impart successive blows. To transmit 100 these blows to the screens, members or pins 35 may be provided projecting through necks 37 on the cover and thence downward into sockets 41 mounted on the screens. The pins for the lower or fine screen project 105 through sleeves 43 mounted on the upper or coarse screen.

To relieve the pins from wear, insure equal blows thereon, and vary the force of the blows, strips 45 may be provided having free ends above the upper ends of the pins, and may be adjustably supported by 110

brackets 47 mounted on the cover, as shown in said application.

To rotate the hammer shafts, they may have sprocket wheels 49 fast thereon connected by a sprocket chain 51. The lower shaft may have a pulley 53 fast thereon driven by a belt 55 from a pulley (not shown) on the screw conveyer shaft to be hereinafter described.

10 Next will be described the disposition of the rotors on their shafts for insuring the striking of the blows of the several hammers in succession. To accomplish this, the rotors are disposed on their shafts at angular intervals of advance, and the sprocket 15 chain and wheel transmission between the two shafts positively maintains the latter in predetermined rotative relation.

In the present instance of the invention, 20 six rotors are provided, three on each shaft, two of which vibrate the upper screen and four of which vibrate the lower screen. The two rotors for the upper screen are mounted on the upper and lower shafts 25 180° apart, (Fig. 8) so that their hammers strike blows at 90° angular intervals. The four rotors for vibrating the lower screen are disposed on their shafts at angular intervals of 90°, (Fig. 7) and the eight hammers carried by said rotors will strike their 30 blows at 45° angular intervals. The rotors may be so arranged that the first two blows will strike the upper part of the screen, the next two blows will strike the lower part 35 of the screen, the next two blows will strike the upper part of the screen, and the next two blows will strike the lower part of the screen.

A desirable order of sequence for the 40 blows for the upper screen is designated by the numbers 1 to 4 at the ends of the hammers shown in Fig. 8; and for the lower screen by the numbers 1 to 8 at the ends of the hammers shown in Fig. 7.

45 The construction is such that the blows of the hammers will follow one another in succession and prevent occurrence of simultaneous blows on the screen. Thus, a highly desirable distribution of blows is maintained, and uniform vibratory effect assured.

50 In some cases it may be desirable to vary the force of the alternate blows produced by the pair of hammers mounted on a rotor. To accomplish this, one of the hammers 33 is reduced as at 33^a so that it may be substantially lighter than its companion. Since these hammers swing freely from their points of pivotal connection with the rotor, their variation in weight will serve 55 to produce blows of different force on the pin.

60 The disposition of the hammers for the upper screen may be such that the first two blows will be heavy and the second two 65 blows will be light; and for the lower screen

the first four blows will be heavy and the last four blows will be light. The reoccurrence of the heavy and light blows will maintain the uniform vibratory effect on the screen. The heavier blows throw the 70 material up from the screen and facilitate the flow of the material down along the screen; whereas, the lighter blows facilitate the passage of the material through the screen.

75 It is frequently desirable to rock the cover of the casing upward (Fig. 1) on its hinges to permit inspection, repair or replacement of the screens. Since the upper screen is suspended by hangers from the 80 cover, it is lifted therewith. This separates the upper screen from the lower screen, and permits convenient access to both.

Heretofore it has been necessary to remove the pins for transmitting the blows 85 from the hammers to the lower screen before lifting the cover, owing to the lateral movement of the pins against the sockets in the lower screen tending to prevent upward movement of the cover. The manual 90 operation of lifting the several pins out through the cover and the replacement thereof is a source of considerable inconvenience.

95 Next will be described means whereby these pins may be automatically lifted with the cover. To accomplish this, each pin may be provided with a stop, in the present instance of the invention, in the form of a cotter pin 57 projecting transversely there- 100 through at a point slightly above the collar on the cover through which the pin passes. This cotter pin is a sufficient distance from 105 said collar to prevent interference with the movement of the pin in transmitting blows from the hammer to the screen, but when the cover is lifted, the pin will slip downward somewhat until the cotter pin engages the top of the collar, and then it will be carried upward with the cover. To render 110 this movement possible, the socket for the lower screen may be provided with a lateral aperture 59 which will allow the side movement of the pin and prevent its interfering with the lifting of the cover. The socket 115 on the lower screen may be variously formed, provided it presents an upper wall which will prevent the flow of the material beneath the socket and the lower end of the pin. The principal function of the socket is to serve as a shield for the pin.

120 When the cover is lowered, the pins will automatically reenter their sockets and assume their proper operative position without attention on the part of the operator.

125 To prevent end thrust engagement of the hammers with the upper ends of the pins or the strips between them, each rotor may be provided with stop means, in the present instance of the invention, in the form of 130

pins 60, which are so located with respect to the hammers that they will limit downward rocking of the hammers into a position where they could have the end thrust engagement, referred to, when rotation of the hammers is commencing or is at a slow speed. During more rapid rotation of the hammers, there is not time for them to gravitate down into engagement with their stops. However, this simple device prevents any possibility of engagement of the hammers with the upper ends of the pins, in such a manner as to react on the hammer shafts and tend to lift the cover.

15 To feed the material to be separated to the screen, the casing may be provided with a feed box 61 at the upper end thereof containing the usual feed screw 63 for conveying the material from one end of the 20 box toward the other, and causing the same to flow over an adjustable feed board 65 and thence down onto a deflecting plate 67 for delivering the material into the space between the upper screen and the cover of 25 the casing.

It will be understood that the invention is not limited to the specific embodiment shown herein, but that various deviations may be made therefrom, without departing 30 from the spirit and scope of the appended claims.

Claims:

1. A separator comprising in combination, a casing, a cover therefor, a screen 35 mounted in said casing, means to percussively vibrate said screen including a member projecting down through said cover toward said screen, means automatically to lift said member from said screen on opening of said cover, and a socket on said screen receiving said member and having a lateral opening allowing side movement of said member as it is lifted.

2. A separator comprising in combination, a casing, a cover therefor, a lower screen mounted in said casing, an upper screen suspended from said cover, means to percussively vibrate said screens including a member projecting down through said upper screen to said lower screen, and means automatically to lift said member from said lower screen with said cover and upper screen.

3. A separator comprising in combination, a casing, a cover therefor, a lower screen mounted in said casing independently of said cover, an upper screen suspended from said cover, means to percussively vibrate said screens including members projecting from said cover toward said upper screen, members projecting from said cover through said upper screen to said lower screen, and means for causing all of said members to move upward with said cover

and upper screen when said cover is lifted 65 to furnish access to said screens.

4. A separator comprising in combination, a casing, a cover therefor, a lower screen mounted in said casing independently of said cover, an upper screen suspended 70 from said cover, means to percussively vibrate said screens including members projecting from said cover toward said screens, hammer means for striking successive blows to said members, and means for lifting said 75 members with said cover and upper screen when the cover is lifted to furnish access to said screens.

5. A separator comprising in combination, a screen, and means to percussively vibrate said screen including a rotor, and swinging hammers pivotally connected to 80 said rotor, one of said hammers being heavier than the other to impart blows to said screen of different force. 85

6. A separator comprising in combination, a screen, and means to percussively vibrate said screen including a rotor, swinging hammers pivotally connected to 90 said rotor, one of said hammers being heavier than the other to impart successive blows of different force, and means to transmit said blows to said screen.

7. A separator comprising in combination, a screen, and means to percussively 95 vibrate said screen including a rotor, and hammers carried by said rotor, one of said hammers being heavier than the other to impart successive blows to said screen of different force. 100

8. A separator comprising in combination, a screen, and means to percussively vibrate said screen including swing hammers having provision for alternately imparting blows to said screen of different 105 force.

9. A separator comprising in combination, a screen, and means to percussively vibrate said screen including a pin, a rotor, swinging hammers pivotally connected to 110 said rotor, and stop means on said rotor to limit the swinging movement of said hammers and prevent end thrust of said hammers on said pin.

10. A separator comprising in combination, a screen, and means to vibrate said screen including pins, and hammer means for striking the pins with alternate heavy and light blows. 115

11. A separator comprising in combination, a casing comprising a rotor carrying a vibratory screen therein, and a vibrating mechanism on said casing, elements of different weights for imparting heavy and light blows to said screen. 120

In testimony whereof, I have signed my name to this specification.

THOMAS J. STURTEVANT.
